UNITED STATES PATENT OFFICE.

HUBERT E. HARRIS, OF ATLANTA, GEORGIA.

RAILWAY-RAIL-FASTENING DEVICE.

1,290,185.

Specification of Letters Patent.

Patented Jan. 7, 1919.

Application filed June 19, 1917, Serial No. 175,651. Renewed June 25, 1918. Serial No. 241,874.

To all whom it may concern:

Be it known that I, HUBERT E. HARRIS, a citizen of the United States, residing at Atlanta, in the county of Fulton and State of Georgia, have invented certain new and useful Improvements in Railway-Rail-Fastening Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in railway rail fastening devices, and the object in view is to produce a simple and efficient apparatus of this nature, in which means is provided for securely holding the spike from loosening, as a train passes over the rails.

Most specifically the present invention comprises a means for holding railway rails, in which a tie plate, upon which the rail rests, is provided, upon its under surface, with a series of notches, adapted to receive the inclined end of the wall of the recess formed in the edge of a spike and coöoperating therewith to securely bind and hold the spike in its clamping relation with the flange of a rail and tie plate, in the particular moment when the stress comes upon the rail incident to the passing of a train over the rails.

The present invention comprises a simple and efficient apparatus of this nature, having various details of construction, combinations and arrangements of parts which will be hereinafter fully described, shown in the accompanying drawings and then specifically defined in the appended claims.

The invention is illustrated in the accompanying drawings which, with the letters of reference marked thereon, form a part of this specification and in which:

Figure 1 is a central vertical sectional view, showing the application of my invention.

Fig. 2 is a top plan view.

Reference now being had to the details of the drawings:

A designates the web of a railway rail, having a flange B, and C is a tie which may be treated with creosote or other composition, and D designates a metallic tie plate,

which has spike receiving apertures H formed therein, and adjacent to each aperture is a notch or indenture E formed in the under surface of the plate. Said plate 60 is provided with lugs projecting from the upper surface thereof and the outer portions of the plate, as at D', are inclined, in order to permit water to drain from the upper surface of the plate. 65

The inner edges of said ribs F are vertical and adapted to contact with one edge of the flange B of the rail.

A spike, designated by letter I, is provided with a head I', designed to engage 70 over the flange of the rail and is provided with a notch N formed in its inner edge, the lower end of the notch having an inclined end wall N'. Said spike is provided preferably with a rear cam portion O and is 75 convexed, as at J, upon its opposite edge, the said shank portion of the spike being preferably of the shape shown in Fig. 1 of the drawings. Said notches formed in the under surface of the tie plate are adapt- 80 ed to receive the inclined end of the wall of the recess formed in the spike, the inclined wall of the notch conforming to the inclined end of the recess, so that when the spike is driven in place in the tie, the spike 85 and plate will interlock, a slight space intervening between the end of the recess and the notch.

The upper surface of the plate upon which the flange of the rail rests is provided with 90 ribs T, making a circuitous passageway, whereby any water which might gather underneath the rail may drain off, and by this construction the weight of the plate is ap- 95 preciably reduced and at the same time ample strength afforded for the purpose for which the same is intended.

In adjusting the parts, the rail is placed upon the tie plate, with the flange against the ribs and the spike passing through the 100 opening in the plate and driven into the tie. As the spike is driven into the tie one edge of the spike will bear against the marginal edge of the spike aperture and will cause the plate to move laterally a slight distance, 105 until the lower marginal edge of the recess in the inner edge of the spike, is slightly above the under surface of the plate. The driving of the spike this distance, will cause the plate D to move laterally a slight distance, and with it the rail, which will be sprung, and when the bottom of the recess

passes below the bottom of the plate, the rail will spring back, carrying with it the plate, thus locking the plate and rail securely to the tie.

5. Plates now employed in railway construction may be provided with the notches without otherwise altering the construction of the plate, thus adapting the invention to standard plates, which are now employed by rail-
10 ways.

When it is desired to remove the spike a claw end of a crow-bar may be inserted underneath the head of the spike and the latter sprung laterally a sufficient distance to per-
15 mit the notch to clear the marginal edge of the spike and the flange of the rail.

What I claim to be new is:

20 1. A railway rail fastening device comprising a tie plate with spike apertures therein, and provided with notches in its under surface, each notch having an inclined wall, a spike having a recess formed in its inner edge, the lower end wall of the recess being inclined, said spike having a laterally ex-
25 tending head for engagement with the upper surface of the flange of a rail, said spike de-
signed to compact the fiber of the tie as it is driven into the latter, and thereby forc-

ing the plate laterally immediately before the notch in the plate interlocks with the re-
cess in the spike.

2. A railway rail fastening device, comprising a tie plate with spike apertures therein and provided with notches in its under surface each notch having an inclined 35 wall, a spike having a recess formed in its inner edge the lower end wall of the recess being inclined, said spike having a laterally extending head for engagement with the upper inclined surface of the flange of a rail, 40 the shank portion of the spike underneath said laterally extending head being convexed intermediate the recess and the point of the spike, the outer portion of the spike slightly below said recess being cam shaped 45 and tending to compress the fiber of the tie and force the plate laterally immediately before the notch in the plate interlocks with the recess in the spike.

In testimony whereof I hereunto affix my 50 signature in presence of two witnesses.

HUBERT E. HARRIS.
